UNITED STATES PATENT OFFICE.

MATTHIAS GARVEY, OF CROWNPOINT, NEW YORK.

WATER-JOINT.

SPECIFICATION forming part of Letters Patent No. 691,539, dated January 21, 1902.

Application filed April 23, 1900. Serial No. 13,915. (No model.)

To all whom it may concern:

Be it known that I, MATTHIAS GARVEY, a citizen of the United States, and a resident of Crownpoint, in the county of Essex and State of New York, have invented a new and Improved Water-Joint, of which the following is a full, clear, and exact description.

This invention is especially adapted for use in connection with diamond rock-drills, the object being to provide superior means for connecting the water-pipe with the drill-rod. Heretofore great difficulty has been experienced in effecting this connection, since it should be understood that the drill-rod must turn continuously, whereas the water-pipe cannot be turned. Owing to the necessary movement of the parts it has been found very difficult to pack the connection between these two elements, and great inconvenience commonly arises. My invention seeks to overcome these objections.

This specification is the disclosure of one form of the invention, while the claims define the actual scope thereof.

Reference is to be had to the accompanying drawings, forming a part of this specification, in which similar characters of reference indicate corresponding parts in all the views.

Figure 1 is a longitudinal sectional view of the invention. Fig. 2 is an elevation with parts in section. Fig. 3 is a section on the line 3 3 of Fig. 1, and Fig. 4 is a detail view of the water-pipe.

Referring to Fig. 1, *a* represents the hollow drill-rod, and *b* the water-pipe. The coupling-thimble *c* has its lower end *c'* reduced and screw-threaded to permit the engagement of the drill-rod *a* therewith. The shoulder formed on the thimble *c* by the reduced end *c'* is provided with a leather packing-gasket *d*, seated in an annular undercut cavity in the thimble and in position to be engaged by the end of the drill-rod, so that when the drill-rod is screwed into the position shown its end engages with the gasket *d* and effects a secure connection therewith, such as will not only effectively prevent leakage at this point, but will also be secure and durable without necessitating frequent repacking, as is the case with the wick packing usually employed in this connection. The width of the gasket *b*, and consequently of the undercut

cavity in the shoulder, is equal to the thickness of the material forming the drill-rod, so that the end of the drill-rod will engage no part other than the gasket.

The thimble *c* has the water-pipe *b* passed centrally therethrough, the water-pipe terminating at the lower end of the extension *c'*, and the upper portion of the thimble is counterbored to form a cavity *c*². This cavity contains a leather cup-packing *e*, which is held between two packing-collars *f* and *f'*, fastened by left-hand threads on the water-pipe *b*. The packing *e* engages firmly with the walls of the counterbore *c*² in the thimble *c* and effects a secure packing at this point, absolutely preventing the backflow of the water through the counterbore *c*² of the thimble. It will further be observed that the form of packing employed being properly lubricated when in use is nearly frictionless, thus rendering the relative movement of the drill-rod and water-pipe easier. The left-hand threads on the water-pipe cause the collars *f* and *f'* to be turned securely thereon by the very operation of the apparatus. Heretofore a plane shoulder has been formed on the water-pipe and wicking wound around the pipe against the shoulder and the pipe forced into position, so that the wicking serves as a packing. The pressure which it is necessary to place on this packing renders the friction so great that it is impossible to drive the drill-rod independently of the water-pipe without tending to turn the water-pipe and disrupt the hose connected therewith.

Into the upper portion of the counterbore *c*² of the thimble *c* I screw a cap *g* for closing the counterbore, such cap having left-hand threads thereon for the same reason that the threads of the water-pipe are left-hand. This cap *g* projects down into the counterbore and bears tightly on a ring *h*, which is sustained on the collar *f'* by bearing-balls *i*, carried in a suitable cage *k*. The pressure of the cap *g* on the ring or collar *h* is transferred to the packing-collars *f* and *f'* through the medium of the bearing-balls, and thus the packing is engaged firmly with the walls of the counterbore. This pressure is transmitted, however, without material increase in friction, owing to the ball-bearings provided between the ring or collar *h* and the packing-ring *f'*, it

being understood that the ring *h* turns with the thimble *c* and cap *g* and that the packing-collars *f* and *f'*, with the packing *e*, are stationary with the water-pipe. By means of this arrangement the drill-rod may be driven continuously at the necessary speed without interfering with the water-pipe, which, owing to the slight friction caused by the relative movement of these parts, will not be disturbed by the rotation of the drill-rod. Further, owing to the effective packing produced by the cup *e* leakage through the thimble is prevented.

It will thus be seen that I provide a most effective packing and at the same time materially decrease the friction caused by the movements of the various parts.

Various changes in the form, proportions, and minor details of my invention may be resorted to without departing from the spirit and scope of my invention. Hence I consider myself entitled to all such variations as may lie within the scope of my claims.

Having thus described my invention, I claim as new and desire to secure by Letters Patent—

1. A water-joint, comprising a thimble, a water-pipe passed therethrough, the thimble having a counterbore therein to form a cavity, a cap screwed into the cavity, a packing carried fast on the water-pipe and situated within the cavity, and ball-bearings placed between the packing and the cap.

2. A water-joint, comprising a thimble, a water-pipe passed thereto, the thimble having a cavity into which the water-pipe extends, and a packing carried by the water-

pipe and seated in the cavity, to pack the interior walls thereof.

3. A water-joint, comprising a thimble with a bore and counterbore, a water-pipe passed through the bore of the thimble, and a packing carried by the water-pipe and situated in the counterbore of the thimble, the packing comprising a cup and rings or the like, the members being fastened to the water-pipe and having the cup sandwiched between them.

4. A water-joint, comprising a thimble with a bore and counterbore, a water-pipe passed through the thimble, a packing carried by the water-pipe and seated in the counterbore of the thimble, a cap fitted in the outer portion of the counterbore, and antifriction-bearing devices interposed between the cap and the packing, to transmit to the packing the pressure of the cap.

5. A water-joint, having a thimble with a reduced extension serving to receive the tubular drill-rod, and the thimble having an annular groove formed in the shoulder at the base of the extension, and a packing-gasket set into said groove and engaged by the end of the tubular drill-rod to pack the same, the width of the packing-gasket being equal to the thickness of the material forming the drill-rod so that the end of the drill-rod engages no part other than the packing-gasket.

In testimony whereof I have signed my name to this specification in the presence of two subscribing witnesses.

MATTHIAS GARVEY.
